UNITED STATES PATENT OFFICE.

ANSEL STEVENS, OF CUMBERLAND MILLS, ASSIGNOR OF ONE-HALF TO JOHN J. FRYE, OF PORTLAND, MAINE.

MOWING-MACHINE.

SPECIFICATION forming part of Letters Patent No. 430,791, dated June 24, 1890.

Application filed November 2, 1889. Serial No. 329,008. (No model.)

To all whom it may concern:

Be it known that I, ANSEL STEVENS, a citizen of the United States, residing at Cumberland Mills, in the county of Cumberland and 5 State of Maine, have invented certain new and useful Improvements in Mowing-Machines; and I do hereby declare the following to be a full, clear, and exact description of the invention, such as will enable others skilled in the 10 art to which it appertains to make and use the same.

My present invention relates to mowing-machines; and it has for its objects, first, to provide means for relieving the pressure of 15 the inner shoe and the finger and cutter bars on the ground, whereby they may be floated or carried so lightly over the ground that they may rise and fall freely to accommodate themselves to unevenness and inequalities in 20 the surface over which the machine travels; second, to provide means for assisting the driver in lifting these parts when, in order to pass obstructions or to drive the machine from one place or field to another, or any 25 other cause, it may become necessary or desirable to raise the entire cutting apparatus and its connected parts bodily from off the ground.

Prior to this invention several constructions and arrangements of devices had been devised to accomplish separately and generally these results, and in a patent granted to me February 27, 1887, Serial No. 187,737, I have shown, described, and claimed an arrangement 35 of counterbalance weight or spring in connection with the hand-lifting mechanism for that purpose; but in this and all other machines where this is attempted, so far as I am aware, the lifting and counterbalancing mechanism 40 has been arranged on the same side of the axle as the hinge-bar and cutting apparatus, from which it results that in front-cut machines when these parts are raised bodily from the ground their weight is transferred 45 to the tongue and thrown almost entirely on the necks of the horses, while in rear-cut machines the tendency is to tip the machine over backward, thereby exerting great upward strain on the necks of the animals. In 50 this invention, however, I overcome these objectionable features and locate the lifting and counterbalancing mechanism over or on

that side of the axle opposite to the cutting apparatus, whereby when the latter is raised bodily, as above described, the weight of the 55 parts exerts no particular strain on the tongue in either direction, but is thrown onto the axle of the machine; and I prefer to mount these lifting and counterbalancing devices so that they may be adjusted forward and back 60 to and from the axle, so that the necks of the horses are not only entirely relieved of the strain, but the machine with the cutting apparatus raised up may be practically balanced on the axle. 65

To this end the invention consists in the construction, organization, and relative arrangement of parts hereinafter particularly described, and illustrated in the accompanying drawings, forming a part of this specification. 70

In the drawings, Figure 1 is a fore-and-aft vertical section of a mower equipped with my improvements. Fig. 2 is a sectional view of the lifting and counterbalancing devices. 75 Fig. 3 is a detail view of the same parts in a different position; and Fig. 4 is a view similar to Fig. 1, with the lifting and counterbalancing devices set so as to operate entirely in rear of the axle. Fig. 5 is a side elevation 80 of a fragment of the lifting and counterbalancing levers as seen from the opposite side to that in Fig. 1.

The frame or main casting of the machine has at or near its rear side a tubular box or 85 sleeve, by means of which it is hung on the axle. This frame is connected with the tongue in the ordinary manner. The hinge-bar (or "coupling bar or frame," as it is often called) and the finger-bar and its appurtenances are, like the frame and the tongue, of the usual construction and arrangement in this class of machines, and need no particular description or illustration to enable those skilled in the art to construct and use them. 90 95

The mower shown in the drawings is of the ordinary front-cut two-wheel type.

Proceeding now to describe my improvements in connection with this class of machine, and reference being had to the drawings, A denotes the tubular axle box or sleeve before referred to. Rearwardly from this sleeve projects the bracket B, upon which are supported and adjustably attached, so as to

be moved to or from the axle, the lifting and counterbalancing mechanism. This mechanism consists of the hand lifting-lever C, pivoted upon a spindle c, projecting laterally 5 from one side of the notched segment-rack D, rising vertically from a suitable base-plate or stand d. This plate is secured to and upon the rearwardly-projecting bracket B by means of bolts passing through fore-and-aft 10 slots d' in the bracket and into holes or perforations b in the rack-plate, receiving nuts b' upon their ends. The lifting-lever is provided, as usual, with the hand-latch c' at its upper end, connected by a rod with the pawl 15 c', pivoted near its lower end, and engaging the teeth on the segmental rack.

Around a short stud E, projecting laterally from the opposite side of the rack from the lever, is coiled the stiff steel spring E', one 20 end arranged to engage a notched rib e on the rack-plate by which it is kept from displacement, and its opposite end bearing against a lug or projection f on the side of the lever, the action of the spring being to 25 tend to force said lever constantly in the direction in which it must be drawn by the operator to lift the cutting apparatus from off the ground. The teeth on the rack-segment D are arranged as shown in Fig. 1, the one 30 on the front side presenting its squared shoulder toward the front, and those on the crown and rear side of the segment pointing in the opposite direction.

Pivoted on the same spindle with the lifting-lever by means of its tubular hub g is a bell-crank lever F. In one adjustment of the lifting and counterbalance mechanism the weight-arm of this lever projects forward, so 35 that the chain G, which extends from the end 40 of this arm, is connected at any convenient point with the hinge-bar H, and hangs down just in front of the axle. In the drawings, Fig. 1, this chain is shown connected to a short arm h, projecting rearwardly from the hinge-bar; 45 but it may be connected to the bar directly or to the diagonal brace H', or in fact to any part of the mechanism which supports the cutting apparatus, whether it be an arm merely or a frame, so long as it rises and falls 50 with the cutting apparatus.

As before stated, the lifting and counterbalance mechanism is made adjustable backward and forward for the purpose of adjusting the weight with relation to the axle. In 55 Fig. 4 it is shown as set back so that the front end of the bell-crank F plays in rear of the axle, and the chain hangs down behind instead of in front thereof. In this adjustment of the mechanism a convenient way of making 60 connection between the forward end of the bell-crank lever and the coupling bar or frame when the lift and counter-balance are in this rearward position is shown in Fig. 4, consisting of a bar I, of iron or steel, having a 65 hook i at its front end, which is caught into an eye h' in the hinge-bar, the bar I extending thence diagonally backward to or in rear

of the axle and passing on its way under the diagonal brace H'. It is not necessary that this bar extend to or past the axle; but the 70 more nearly it approaches the vertical plane of the front end of the bell-crank lever the more nearly vertical the chain will hang and the more easy the action of the parts will be.

Coiled around the hub g of the bell-crank 75 lever is a steel spring L, one end bearing in a notch in the base-plate of the segment and the opposite end against a lug l' on the rear arm of the bell-crank. This bell-crank, it will be observed, is freely pivoted on the 80 same axis as the hand-lever. It lies close beside the latter, and has a free and easy movement independent of the latter. It is, nevertheless, constructed and arranged in relation to the hand-lever so that it will be drawn 85 back by the latter in raising the cutting apparatus. The rear arm of the bell-crank is provided with a laterally-projecting pin or detent f, which stands in the path of the hand-lever, which pin is struck by said lever 90 in its backward movement, causing the bell-crank to rock with the lever in that movement. The spring L, which is coiled around the hub of this bell-crank and reacts between the frame and the arm of the bell-crank, is 95 the counterbalance-spring. Its function is, primarily, to lessen the pressure of the inner shoe and the finger-bar on the ground, whereby the friction of the cutting apparatus is 100 lessened, side draft is reduced, and part of the weight of the cutting apparatus is transferred to the machine, thus increasing the traction of the drive-wheels. The spring E, reacting between the lifting-lever and the frame, however, plays no part in the function 105 of floating or lessening the weight of the cutting apparatus on the ground, but is designed solely for the purpose of assisting the driver in the operation of raising the entire mechanism off the ground by relieving him of part 110 of its weight. The counterbalance-spring having the less work to do, not being intended to do more than relieve the pressure of the cutting apparatus on the ground, is made lighter or of less strength than the lifting- 115 spring. The action of the lifting-spring is independent of the counterbalance-spring, though the latter aids and assists the former in its lifting function. The lifting-spring is 120 of course made heavier than the counterbalance-spring; but it need not be made so stiff as other lifting-springs must be whose action is not supplemented by a counterbalance.

While the machine shown in the drawings, and in connection with which the invention 125 has hereinabove been described, is of the now common and popular two-wheel front-cut type it is obvious that my invention is also applicable to the equally-well-known rear-cut machines. In applying it to such machines the 130 positions of the lifting and counterbalancing levers and the hinge-bar with relation to the axle would simply be reversed.

From the above description the operation

of the parts will be clear. In action the hand-lever is thrust forward till its pawl drops down in front of the foremost tooth of the rack. In this position the weight of the cutting apparatus will pull down the front arm of the counterbalance-lever till the finger-bar rests lightly on the ground ready for use. The stress of the lifting-spring tending constantly to throw the hand-lever back prevents it from wabbling with the jolting and jarring of the machine, and holds it firmly against the rack-tooth within convenient reach of the driver in his seat. The counterbalance-spring tends also to lift the finger-bar, but, not being sufficiently stiff, only takes part of its weight off the ground, and, tending to throw the bell-crank back, keeps the connecting chain always taut, the bell-crank rocking freely on the axis of the hand-lever as the shoe rises and falls in its movement over the ground. When it is desired to raise up from the ground the entire cutting mechanism, the driver unlocks the pawl from the rack, and if the spring has not been made sufficiently stiff to do the work alone, pulls the lever back. In this movement the back of the lever strikes the pin or detent on the rear arm of the bell-crank, and carries that lever back with it, pulling on the chain and lifting the whole cutting apparatus. Of course the nearer the point of suspension of the lifting and counterbalance mechanism to the axle the less strain will be thrown on the necks of the team, and the farther that point is adjusted to the opposite side of the axle from the hinge or coupling bar the more perfectly the weight of the frame and tongue and the parts supported thereby will be balanced on the axle.

I do not wish to be understood as limited to the details of the construction or arrangement herein shown, as the invention is susceptible of variation within considerable limits.

Having thus described my invention, what I claim is—

1. In a mower, the combination of the frame pivoted on the axle, a lifting-lever mounted on the frame so as to be adjusted forward and backward, and a chain-connection between the lever and the hinge-bar, substantially as described.

2. In a mower, the combination of the frame pivoted on the axle, a counterbalance spring-lever mounted on the frame so as to be adjusted backward and forward thereon, and a chain-connection between the lever and the hinge-bar, substantially as described.

3. In a mower, the combination of the frame pivoted upon the axle, a bracket projecting from the frame on one side of the axle, a lifting-lever mounted on said bracket, and a direct chain-connection between said lever and the hinge-bar on the opposite side of the axle from the bracket, substantially as described.

4. In a mower, the combination of the frame pivoted on the axle, a bracket projecting from the frame on one side of the axle, a spring

counterbalance-lever mounted on the bracket, and a direct chain-connection between the lever and the hinge-bar on the opposite side of the axle from the bracket, substantially as described.

5. In a mower, the combination of the frame pivoted on the axle, a bracket projecting from the frame on one side of the axle, a lifting-lever mounted on said bracket so as to be adjusted forward and backward, and a direct chain-connection between said lever and the hinge-bar on the opposite side of the axle from the bracket, substantially as described.

6. In a mower, the combination of the frame pivoted on the axle, a bracket projecting from the frame on one side of the axle, a spring counterbalance-lever mounted on the bracket so as to be adjusted fore and aft, and a direct chain-connection between the lever and the hinge-bar on the opposite side of the axle from the bracket, substantially as described.

7. In a mower, the combination of the frame pivoted on the axle, a hand-lever mounted on the frame, an independent spring counterbalance-lever pivoted on the same axis as the hand-lever, a pin on the counterbalance-lever overlapping the back of the hand-lever, and a direct chain-connection between the counterbalance-lever and the hinge-bar, substantially as described.

8. In a mower, the combination of the frame pivoted on the axle, a segment-rack on the frame, a hand-lever pivoted concentric to the rack, a spring reacting between the lever and the frame, a counterbalance-lever pivoted on the same axis as the hand-lever, a spring reacting between this lever and the frame, the hand-lever having a hand-controlled pawl engaging the rack, the counterbalance-lever having a projection arranged to be struck by the back of the hand-lever, and a chain connecting the counterbalance-lever with the hinge-bar, substantially as described.

9. In a mower, the combination of the frame pivoted on the axle, a segment-rack on the frame, a hand lifting-lever, a stiff lifting-spring reacting between the lever and the frame, a counterbalance-lever pivoted on the axis of the hand-lever, a weaker spring reacting between it and the frame, the counterbalance-lever having a projection overlapping the back of the hand-lever, and a chain connecting the counterbalance-lever with the hinge-bar, substantially as described.

10. In a mower, the combination of the frame, a lifting-lever and a counterbalance spring-lever mounted thereon on one side of the axle, and a direct chain-connection between the counterbalance-lever and the hinge-bar, said bar being on the opposite side of the axle from the levers, substantially as described.

11. In a mower, the combination of the frame pivoted on the axle, the bracket B, pro-

jecting therefrom in rear of the axle and having the slots d' , the segment D, its base-plate d , having the bolt-holes b , the bolts and nuts, the hand-lever C, pivoted on the spindle 5 c , concentric with the rack, the heavy lifting-spring E, reacting between the hand-lever and the frame, the bell-crank-lever F, pivoted on the same axis with the lifting-lever, the relatively light counterbalancing-spring 10 L, reacting between the frame and the rear arm of the bell-crank, the projection f on said rear arm overlapping the back of the lifting-

lever, and the chain G, connecting the front arm of said lever with the hinge-bar or coupling-frame, the segment-rack having the square-faced tooth on its front side and the rearwardly-facing ratchet-teeth on its rear part, substantially as described. 15

In testimony whereof I affix my signature in presence of two witnesses.
